UNITED STATES PATENT OFFICE.

ARTHUR NELSON, OF VANCOUVER, BRITISH COLUMBIA, CANADA.

CARDBOARD BOX.

Application filed October 25, 1921. Serial No. 510,260.

To all whom it may concern:

Be it known that I, ARTHUR NELSON, citizen of the Dominion of Canada, residing at Vancouver, in the Province of British Columbia, Canada, have invented certain new and useful Improvements in Cardboard Boxes, of which the following is a specification.

This invention relates to a cardboard box 10 of that class wherein a rectangular inner container is endwise movable within a corresponding outer casing, and the invention comprises the combination therewith of an endwise movable strip of paper on which a 15 series of pictures or advertising matter is set forth, which, by endwise pulling the strip, are successively displayed through an aperture cut in the outer casing.

The invention is fully described in the 20 following specification, reference being made to the drawings by which it is accompanied, in which:

Fig. 1 shows the box in perspective during the earlier stages of the operation of 25 the strip.

Fig. 2 is a vertical section through the box on the plane 2—2, and

Fig. 3 shows the inner box blank as folded.

The inner container may be folded in any 30 convenient manner, but the blank is preferably cut that the faces 2 and the sides may be folded upward from an end 3 and the other end 4 be infolded to close the container.

This container is endwise movable within 35 an open ended rectangular outer casing 5. In one outer face of 5 is cut a narrow rectangular aperture 6. A strip 7 of paper or similar flexible material of such width that it will freely move through the casing 40 5, is wrapped endwise around the container 2, 3, 4, one end being folded inside the other end 8 on the back of the container, which end 8 projects beyond the adjacent end of the 45 box. On this strip 7 from that position of it which is adjacent the aperture 6 to the infolded end, a series of pictures 9 or panels of advertising matter corresponding to the aperture 6 are set forth.

As the strip 7 is slowly withdrawn by 50 pulling on the projecting end 8 while holding the box with the other hand, the pictures 9 will be successively displayed through the aperture 6 of the casing 5.

To prevent the tension on the end 8 from 55 drawing the container 2, 3, 4 endwise out of

the casing 5, tabs 10 are left adjacent one end 3 or 4, which tabs, when the container is within the casing 5, may be held by the finger and thumb against the sides of the 60 casing and hold the container 2, 3, 4 in the casing while the strip 7 is being drawn endwise to successively expose the pictures 9 through the aperture 6.

The essential feature of the invention lies 65 in the relation of the endwise movable strip 7 to a boxlike container and its cover whereby the strip may be endwise drawn through the cover to display successively through an aperture in the cover the pictures 70 or printed matter on strip.

The device may be used in many ways as 75 an attractive selling feature for the contents of the box, or as illustrating or describing the use of the contents.

Having now particularly described my invention, I hereby declare that what I claim as new and desire to be protected in by Letters Patent, is:

1. The combination with a container, of a 80 cover therefor having a display aperture and a strip of flexible material passing between the sides of the container and the cover, said strip having a succession of panels of printed matter on the face toward the cover 85 which when the strip is pulled endwise will be successively displayed through the aperture of the cover.

2. The combination with a container, of 90 an open ended casing within which the container is endwise movable, said casing having a display aperture in its wider side adjacent one end, a strip of flexible material folded around the container to leave a finger engaging end downwardly projecting 95 from the side and end of the container opposite the position of the aperture in the casing, the other end of which strip is folded under the downwardly projecting end, the outer face of said strip from above the 100 aperture to the inwardly folded end having printed matter displayed on it in panels approximately corresponding to the display aperture.

3. The combination with a container having 105 tabs projecting from one of its ends, of an open ended casing within which the container is endwise movable and over the ends of which the projecting tabs of the container are foldable, said casing having an aperture 110 in one of its wider sides adjacent one end, and a strip of flexible material folded

around the container, one end of which strip projects beyond the end of the container and the other end folded on the container under the projecting end, said strip having a series of panels printed with pictures or the like, said panels approximately corresponding to the size of the aperture in the casing, whereby the container with the folded strips

being inserted in the casing with the tabs out-folded over the sides of the casing, the strip may be slowly withdrawn and successively display the panels through the aperture.

In testimony whereof I affix my signature.

ARTHUR NELSON.
